UNITED STATES PATENT OFFICE.

ALLISON A. CLOKEY, OF RUTHERFORD, NEW JERSEY, ASSIGNOR TO WESTERN ELECTRIC COMPANY, INCORPORATED, OF NEW YORK, N. Y., A CORPORATION OF NEW YORK

VIBRATION DEVICE.

Application filed December 29, 1923. Serial No. 683,304.

This invention relates in general to vibrating devices and more particularly to a means for controlling the rate of vibration of electrically driven tuning forks.

5 In various telegraph systems such, for example, as the well known multiplex systems, it is necessary for satisfactory operation to maintain the apparatus at the separated stations in very close synchronism. Approximate synchronism is ordinarily obtained by driving the mechanism at the respective stations by means of an impulse motor of the La Cour type, the impulses for which are obtained from carefully adjusted tuning forks.

10 15 arranged to be electrically driven. However, irrespective of the care with which such forks are adjusted, they do not operate in sufficiently close synchronism to provide satisfactory results and it becomes necessary to provide 20 at one of the stations, means for automatically correcting the rate of vibration of the fork at that station to conform to the rate of vibration of the fork at the controlling station. In order to obtain sufficiently close 25 adjustment of the fork to permit satisfactory correction, it has been a common practice to provide a pair of weights which are slideable along the fork tines by means of an adjusting screw, thus varying the frequency of vibration 30 of the fork. Such an arrangement, however, has been found to be unsatisfactory for use with printing telegraph apparatus operating at high speeds on submarine cables, since the rate of vibration of the fork varies a small 35 amount which makes it practically impossible to obtain sufficiently close correction of the controlled fork when operating under such rigid conditions and at high speeds. This variation was found to be due to a slight change 40 in the position of the weights as a result of the vibration of the fork, thus causing a corresponding change in the rate of vibration. Since it is often required to make small 45 adjustments on the fork while it is in operation, it has not been found satisfactory to remedy this condition by locking the weights in position.

The object of the present invention is to provide a frequency adjusting means for vibrating devices, such as electrically driven tuning forks, which will not change in adjustment, and one whereby the fork may be

quickly and accurately adjusted while in operation.

To accomplish this object, the invention 55 contemplates the use of electromagnetic means cooperating with the fork tines to vary their effective stiffness.

The invention may be more clearly understood by reference to the accompanying drawing 60 in which there is disclosed an electrically driven tuning fork provided with an adjusting device embodying the features of the invention.

Referring to the drawing, the fork 5 which 65 is connected to a source of power such as the grounded battery 6, is maintained in operation by means of the electromagnet 7. One terminal of the operating electromagnet is grounded and the other terminal is connected 70 to a contact spring 8 which cooperates with the fork tine 9 to provide a buzzer contact controlling the energization of the electromagnet and consequently the vibration of the fork tines 9 and 10. A pair of contact springs 11 75 and 12 located on opposite sides of the tine 10 and alternately engaged thereby, serve to impress current impulses from battery 6, alternately on magnets 13, 13 and 14, 14, of a La Cour motor of the well known type which 80 drives the synchronous mechanism at that station.

An electromagnet 15, the core of which is provided with pole faces 16, 16 of the same dimensions as the ends of the fork tines, is 85 rigidly mounted on the base of the fork in the position as shown, the air gaps between the pole faces and the fork tines being made as small as possible without permitting the parts actually touching each other. The 90 winding of electromagnet 15 is connected to a source of energy 17 in series with a variable resistance 18 and a current indicating device 19.

When the fork is set in vibration as by 95 plucking, its operation is maintained by the intermittent current impulses flowing through electromagnet 7, and current impulses from battery 6 are thus transmitted to the operating magnets of the La Cour motor 100 in the standard manner. The magnetic effect due to the energization of electromagnet 15 serves to increase the apparent stiffness of the tines of the fork and thereby produce and in-

crease in its rate of vibration. This rate of vibration can be varied within sufficiently wide limits for practical purposes by the adjustment of the variable resistance 18. The 5 indicating device 19 is preferably calibrated to indicate the percentage change in fork frequency, thus permitting the operator to tell the operating frequency at a glance.

The method of varying the frequency as 10 described above, has been found superior to methods previously employed and is satisfactory under the rigid requirements of submarine cable operation. Not only is the adjustment easy to make, but it can be accurately made while the fork is in vibration 15 and then remains constant.

What is claimed is:

1. In a tuning fork including a pair of 20 vibrating tines, means for maintaining said fork in vibration, and electromagnetic means independent of said first named means cooperating with said tines magnetically to control their rate of vibration.

2. In a tuning fork including a pair of 25 vibrating tines, means for maintaining said fork in vibration, electromagnetic means independent of said first named means cooperating with said tines magnetically to control their rate of vibration, and means for controlling said electromagnetic means.

3. In a tuning fork including a pair of 30 vibrating tines, means for maintaining said fork in vibration, electromagnetic means cooperating with said tines to control their rate of vibration, means for controlling said electromagnetic means, and means for indicating the frequency of vibration of said fork.

4. In a tuning fork including a pair of 35 vibrating tines, means for maintaining said fork in vibration, and electromagnetic means cooperating with said tines magnetically to control their rate of vibration, said electromagnetic means including a core having its 40 pole faces in operative relation with said fork tines and acting to increase the natural period of vibration of the fork.

5. In a tuning fork including a pair of 45 vibrating tines, means for maintaining said fork in vibration, and electromagnetic means cooperating with said tines to control their rate of vibration, said electromagnetic means

including a core having its pole faces in alignment with and in close relation to the free ends of said fork tines.

55

6. In a tuning fork including a pair of 60 vibrating tines, means for maintaining said fork in vibration, and electromagnetic means cooperating with said tines to control their rate of vibration, said electromagnetic means including a core having a pair of pole faces substantially equal to in dimension and mounted closely in engagement with the free ends of said fork tines.

7. The method of varying the frequency 65 of a vibrating member which consists in subjecting said member to a constant magnetic force.

8. The method of varying the frequency of 70 an electrically driven tuning fork including a pair of vibrating tines, which method consists in including said fork tines as a portion of a magnetic circuit and subjecting said magnetic circuit to a constant flux.

9. The method of adjusting the period of 75 vibration of a constantly driven tuning fork having magnetic material in the tines, without bringing the tines to rest, which comprises setting up a magnetic field of the requisite strength in said magnetic material, 80 said magnetic field tending to increase the frequency of vibration of said fork.

10. The method of adjusting the frequency 85 of vibration of a constantly driven vibrating element comprising magnetic material, without bringing the element to rest, which comprises varying the strength of a magnetic field in which the magnetic material vibrates, 90 said magnetic field tending to increase the frequency of vibration of the vibrating element.

11. A vibrating system comprising a vibrating element having a vibratory magnetic portion, driving means therefor, in combination with frequency control means independent of said driving means, comprising a magnetic stationary element and means for setting up a substantially continuous magnetic flux in a magnetic circuit including said vibratory magnetic portion and at least a portion 100 of said stationary element.

In witness whereof, I hereunto subscribe my name this 26 day of December, A. D. 1923.

ALLISON A. CLOKEY.
